CASTER SOCKET

Edward A. Brokaw and William H. Noelting,
Evansville, Ind., assignors to Faultless Caster
Corporation, Evansville, Ind., a corporation

Application March 1, 1934, Serial No. 713,451

5 Claims. (Cl. 16—39)

This invention relates to a socket type frame for mounting upon and within a tubular leg and adapted to receive the stem of a load supporting caster.

5 The present invention is particularly directed to standardization.

The chief object of the invention is to provide a part which can be standardized and utilized substantially for frames for the legs of different sizes by the addition of one or more plate members and the corresponding enlargement of the spring arm means, which frictionally engage the interior of the tubular leg with which the entire frame structure is associated.

15 The basic element of the combination includes a socketed body which at its lower end is provided with an outwardly directed flange and adjacent thereto is an enlargement substantially the cross sectional area of the smallest tubular leg with which sockets of this general type are associated. The socketed body includes an elongated bore therein having its opening at the lower face and providing a closed end.

20 Adjacent the closed end is a reduced portion forming a shoulder and immediately above the same is an enlargement. If and when desired, an additional shoulder portion may be provided and when thus provided, it constitutes a seat for an upper plate or washer, the latter constituting the upper centering structure. Said arm means and the upper washer are secured to the socketed body by lateral enlargement of a coaxial portion (the enlargement) of the socketed body at the end opposite the opening therein.

25 Various forms of spring arm means and various forms of plate means are illustrated. Whenever the tubular portion of the tubular leg, with which the socket frame is to be associated, is of relatively large cross sectional area, a supporting, 30 and in some instances a supporting and centering lower plate, is associated with the socketed body, as well as the upper centering plate. It is thereby possible to use the same socketed body for a wide range of caster socket frames by merely 35 changing the spacing of the spring frame arms and by providing the proper upper, and if desired as well, the lower centering plates for the size of tubing or leg to be accommodated.

40 The central tubular body is, as will be apparent from the drawings, capable of automatic screw machine production. The upper washer is capable of formation from a flat sheet by punching and the lower washer is capable of production by a punching operation. The spring frame arms 45 preferably are of stamped formation, in most in-

stances being formed from strip spring metal cut to length and properly formed. In certain forms of the invention, wider stock must be utilized. The spring frame arm means are preferably made from two or three widths of strip spring metal; the smaller width strips being utilized for the smaller frame sizes and the intermediate or larger strips being utilized for the larger frame sizes. In certain instances, however, particularly when more than a pair of spring arms are 50 to be utilized, the smaller width stock may be utilized for the larger size frames.

The full nature of the invention will be understood from the accompanying drawings and the following description and claims:—

Fig. 1 is a central sectional view through what may be termed the smallest size socket embodying the invention, the dotted lines indicating a tubular leg for which said socket is adapted for use.

Fig. 2 is a top plan view of the socket shown in Fig. 1.

Fig. 3 is a view similar to Fig. 1 of a larger size socket including a load supporting plate.

Fig. 4 is a top plan view thereof.

Fig. 5 is a view similar to Fig. 3 and of a modified form, this form including two pairs of diametrically spaced arms transversely positioned as distinguished from one pair of diametrically positioned arms utilized in the form shown in Figs. 1 and 3.

Fig. 6 is a top plan view thereof.

Fig. 7 is a central sectional view through a modified form of the invention, wherein the spring arms means is of the peripheral type as distinguished from the longitudinal strip type previously illustrated.

Fig. 8 is a central sectional view similar to Fig. 7 and of a still further modified form of the invention, this form differing from Fig. 7 chiefly in the inversion of the lower peripheral spring structure.

Fig. 9 is a central sectional view of still a further modified form of the invention wherein the spring frame is shown detachably associated with both the upper end of the tubular socket and the lower load sustaining washer or plate.

Fig. 10 is an elevational view of a form of the invention similar to Fig. 3 and illustrates a modified form of lower load sustaining plate and arm connection.

Fig. 11 is a view taken at right angles to Fig. 10 and of the same socket.

In Fig. 1 of the drawings, A indicates the tubular leg having the opening B therein, and the lower edge C.

The frame socket is herein shown comprising a tubular body 10 having an elongated bore 11 therein opening on the face 13 and its upper end being closed by the wall 14 which forms a top bearing for a caster stem which is receivable by and suitably retained in the bore 11.

The lower end of the tubular body 10 is provided with a flange 15 that projects as at 16 beyond an enlarged portion 17 having the upwardly tapered portion 18.

The upper end of the tubular body is reduced as at 19 to form a shoulder and is additionally reduced as at 20 to form a second shoulder. A portion 21 projects axially from the body and is adapted for lateral enlargement in a bulldozer or header for forming the enlargement 22.

Suitably encircling the tubular body and seated on shoulder 19, is a plate or washer 23 and suitably seated upon shoulder 20 is a central portion 24 apertured as at 25. The portion 24 is formed from a strip and is centrally positioned with respect to the ends of said strip. The portion intermediate the central portion and the ends, is positioned in spaced relation to the body and is slightly bowed outwardly forming spring frame arms 26.

When the socket frame is mounted in the opening B of the tubular leg A, the lower end C of the leg engages the upper face 16 of the flange 15, and the interior wall of the leg A is engaged by the diametrically positioned spring frame arms 26, the length of which is so adjusted that the arms can be accommodated within the tubular leg and at the same time insure maximum frictional gripping thereof.

In this form of the invention, as indicated at 27, the washer 23 is provided with a pair of flat faces. The spring frame arm means and the washer 23 thus are rigidly clamped to the tubular socket by the lateral enlargement 22 of portion 21 and the flat faces 27 register with arms 26.

In Fig. 3 a modified form of the invention is illustrated, and in this form the same tubular body 45 is employed. However, instead of the tubular leg bearing directly upon flange 15, there is interposed a bearing plate 28 that is of a diameter or cross sectional area slightly greater than the outside diameter or cross sectional area of the tubular leg A'. The plate 28 has a central opening 29 which is substantially the diameter of the enlarged portion 17 of the tubular body.

Also mounted on the tubular body and resting on plate 28, is another plate or washer 30 which is provided with notches or slots 31 therein diametrically positioned to accommodate the lower free ends of the spring frame arms 126. The shoulder portion 19 of the tubular body 10 supports another plate or washer 123 which is substantially identical to the plate 30 and which is also notched or slotted as at 127 substantially the same as at 31 and the notches and slots 131 and 127 register. In this form of the invention, the central portion 124 of the spring frame arm means is of considerably greater length than that shown in the modification in Fig. 1. The upper washer or plate 123 thus serves as a top centering member for the spring frame socket and the lower plate 30 also prevents lateral play of the socket structure at the lower end. In certain forms of the invention, the plate 30 and the plate 28 may be formed as a single member and whenever formed of sheet metal, it may be substantially like that shown in Figs. 10 and 11, and if formed of the

cast metal, it may be like that shown in Fig. 3, although then it would be in one piece.

The modifications shown in Figs. 5 and 6 only differ from that shown in Fig. 3 by the addition of a second U-shaped spring structure and the formation of each spring frame structure from a spring metal strip of a width greater than that shown in Figs. 2 and 4. In said figure, the shoulder 16 of the flange 15 supports a plate 28 which is of the desired outline corresponding to the 10 outline of the tubular leg.

Suitably supported thereby is a washer 130 which in place of having a single pair of diametrical slots 131, is provided with two pairs of diametrical slots 131, these two pairs being transversely positioned. The shoulder 19 supports a plate 223 provided with four quadrantly arranged slots 227 and the slots 131 and 227 register.

The shoulder portion 20 of the tubular body supports two transversely arranged and centrally apertured U-shaped spring frame members, each having the central portion 124, the depending free arm portions 126 and the centrally apertured portion 125. These two central portions cross each other as shown in Fig. 6. Thus, this form 25 of the invention, as before stated, only differs in that it utilizes four spring arms in place of two and that one spring arm is mounted above the other and in view of the length of the slots 131, either spring arm structure may be used interchangeably with the other. The two U-shaped spring arm members are suitably secured in clamping relation by means of the shoulder 20, shoulder 19, enlargement 22 and the plate 223.

In Fig. 7 of the drawings, there is illustrated 35 a modified form of the invention, wherein 115 indicates the flange providing the shoulder 116 supporting the plate 128 which encircles the enlarged portion 117, shouldered as at 118. The tubular body 110 is provided with a bore 111 that opens 40 on the face 113, the bore at its opposite end being closed as at 114. The tubular body is provided with shoulder 119 and the reduced portion 120 of considerable length. The central coaxial portion 121 is enlarged laterally as at 122 to clamp 45 between shoulder 119 and the portion 122, the tubular collar portion 325 defining the central opening in the dished plate portion 324 from which at the extremity of the plate portion projects a plurality, and herein four are illustrated, 50 of connected spring frame arms 326. These extend outwardly and downwardly, thereby facilitating nesting in the insertion of the entire socket within the tubular leg.

A somewhat similar but slightly different peripheral spring structure includes the collar portion 425, the dished central plate portion 424 and the upwardly and outwardly extending connected arm portions 426, which have inwardly directed ends 426a to facilitate mounting of the entire 60 structure within the tubular leg. The adjacent ends of the upper and lower spring cup supported arms in the mounting of the spring frame socket are caused to move inwardly toward each other and thus exert frictional stress upon the interior 65 of the tubular leg for the mounting of said socket. The lower spring cup is suitably secured in clamped relation relative to the shoulder 118 by a plurality of enlargements or a single peripheral enlargement 100.

In Fig. 8 there is illustrated a modified form of the invention wherein 210 indicates a tubular body provided with a bore 211, closed by a top bearing wall 214 and provided with a mouth opening upon the face 213 and defined by a flange 215 75

having the shoulder 216. The enlarged portion 217 is reduced as at 218 and the plate 228 is adapted to support the tubular leg by engaging the lower end thereof. The upper end of the 5 tubular body 210 is reduced as at 219 and the central portion 220 supports the retaining portion 221 having the laterally enlarged portion 222, between which portions 222 and 219, is clamped the spring frame cup substantially similar to the upper cup shown in Fig. 7, except that the tubular collar is omitted. Herein said cup 10 includes the central portion 524 having the central opening 525 and the downwardly and outwardly directed connected arms 526.

15 In this form of the invention a second and lower cup includes the central portion 624 with a central aperture 625 and the downwardly and outwardly directed connected arms 626 which terminate just above the plate 128. This cup is 20 retained in position on the tubular body by the portion, or portions, 280. In the present instance, the plate portion 624 is not provided with a collar such as the portion 425, so that this form 25 of the invention, while similar in many respects shown in Fig. 7, differs therefrom in two respects—first, the inversion of the lower cup and second, the omission of the central open defining collar portions from both of said cups.

30 In Fig. 9 of the drawings, there is illustrated a further modified form, this form being capable of reproduction in a plurality of different sizes while utilizing the same size socket body by merely associating therewith the predetermined size of spring structure and the supporting plate 35 or flange corresponding thereto, it being understood that the central portion of each of the spring structures, is fashioned with the same die and that the respective supporting plate is provided with the same size central opening.

40 In Fig. 9, 310 indicates the tubular body having the bore 311 therein opening on the face 313 of the flange 315 providing shoulder 316, enlarged portion 317 and the upwardly tapered portion 318. The bore is closed by the top bearing surface 314. The upper end of the tubular body is reduced as at 320 providing the upper relatively enlarged portion 322 and the lower relatively enlarged portion 319 adjacent thereto. This forms an annular groove to receive inturned 45 portions 725 depending from the central portion 724 which is formed from the strap providing the U-shaped edges diametrically opposite each other as at 725a. Each arm 726 is arcuate in section and at its lower end terminates in an outwardly directed portion 726a forming an interior groove 726b and an underlying portion 726c. Groove 726b and portion 726c, respectively, receive and support the spacing plate 328 resting on shoulder 316. The tubular leg engages the outwardly directed portion 726a and is supported thereby in this engagement. The two spring arms are forced inwardly, the inward movement being limited by the plate 328 so that said portions 726a are adapted to support the load and to prevent 55 cocking of the entire socket at its lower end. Plate 328 insures substantial central positioning of the tubular body portion within the tubular leg, and the load is transmitted to the caster stem thereby.

70 This form of the invention is of the detachable spring frame type and as stated, spring frames having substantially the same central formation, may be substituted one for the other and associated with the tubular body 310 and the corresponding plate 328 of the desired external

cross sectional outline in area and having a central opening of the same diameter is utilized therewith and thus an entire series of detachable sockets may be readily manufactured through the utilization of the same central forming die 5 for the spring frame and the utilization of the same tubular body 310.

10 In Figs. 10 and 11 there is illustrated a modified form of the invention and herein the same is shown including a pair of diametrically positioned spring frame arms, although it is readily apparent that in exactly the same manner that Figs. 5 and 6 differ from Figs. 3 and 4, an extension of the form of the invention shown in Figs. 10 and 11 may be made, which would include two 15 transversely positioned diametrical pairs of spring frame arms, in which event the lower supporting and spacing plate instead of being provided with two apertures and two tongues, would be provided with four apertures and four tongues 20 in quadrant relation.

25 In Fig. 10 the same tubular body shown in Figs. 1 and 3, is utilized and likewise the same type upper washer or plate is utilized, and approximately the same spring frame is utilized, except that each of the arms 826 at their lower ends are reduced as at 826a to form a tongue 826b. In this form of the invention the two lower plates 28 and 30, shown in Fig. 3, are formed as a single 30 plate structure. Herein the peripheral portion 428 is adapted to engage the lower end of the tubular leg and support the same. The embossed portion 428a is suitably slotted as at 428b forming an upwardly directed tongue 428c and the slot 428b receives the reduced end 826b of the 35 spring frame arm and the tongue 428c serves as a stop to prevent radial inward movement of the spring frame arm as its lower end. The purpose of this is to insure as much as possible full line contact of the arm with the leg interior along 40 one or more longitudinal elements of said tubular leg.

45 The plate portion 430 is apertured as at 431 and is telescopically receivable by the large portion 17 of the tubular body 10. In view of the fact that the load is applied to the plate portion 428, it is not necessary to provide a rigid anchorage for the plate portion 430 to insure against upward movement of said plate upon the portion 17. This consideration also eliminates the necessity 50 for preventing upward movement of plate 228 in Fig. 9, whereas in Figs. 7 and 8 the portions 100 and 200 respectively are provided to prevent upward movement of the lower portion of the lower cup structures, because they are relatively independent of the load supporting plate portion.

55 It is not necessary also in the forms of the invention shown in Figs. 3 and 5 to provide means for holding down the lower plates 30 and 130, because they are not subject to any upward movement or force from the arms and they have sufficient weight to seat by gravity upon the load supporting plate, plates 30 and 31 being solely provided to insure against undue inward movement of the free ends of the spring arms.

60 It will be apparent from the aforesaid that each and every form of the invention consists of the spring frame structure of two or more arms or their cup equivalents providing substantial full line contact throughout the length of the socket 70 and wherein the inward movement of the free portions of the spring frame means at each end of the frame is limited, either inherently by its construction or by the use of other means operatively associated therewith, and in each instance 75

the spring frame structure provides a centralized upper centering device and a centering device at the lower end of the spring frame structure to prevent cocking of the tubular body and to insure maintenance of it in centralized position within the tubular leg.

Since portions 17, 18 and vertical portions adjacent 19 and 20 upon which the washer and spring frame means are mounted may be of circular cross-section, the entire spring and centering structure may swivel on the tubular body 10, in Figs. 1 to 6 and 10 and 11, if the enlargement 21 is not pressed down unduely, that is, to rigidly clamp said structure to the tubular body. The 15 interlocking relation of the washers or plates and the spring means insure unit swivelling. Of course, the form shown in Fig. 9 may swivel on body 310.

The invention claimed is:—

20 1. A spring frame type socket for tubular legs including a body portion having an elongated caster stem receiving bore therein terminating in a top bearing for the stem, an annular, grooved portion adjacent the upper end, and an outwardly directed flanged lower end adapted to transmit leg load to the stem, spring frame means swivably mounted in said grooved position, and other means rotatably mounted upon said body and operatively associated with the spring frame 25 means.

20 2. Semi-standardized spring frame type sockets adapted for reception by cylindrical tubular legs of various commercial diameters, each including a standardized body portion for all diameters of legs and having a caster stem receiving bore therein terminating in a stem top bearing, an annular portion of slightly lesser diameter than the leg diameter and positioned upon the upper end of the body portion and prevented 30 against axial movement thereon, another annular portion of slightly lesser diameter than the leg diameter and positioned upon the body below and in spaced relation to the first mentioned annular portion, said annular portions locating axially 35 the standardized body in the cylindrical leg, a load sustaining annular portion projecting laterally from the lower portion of the body to and beneath the leg for transmitting leg load to the body, and a spring frame operatively associated 40 with the upper portion of the body and having a plurality of downwardly extending arms radially spaced from the body axis approximately the 45

radius of the selected tubular leg, a plurality of said annular portions except for the smallest size socket being elements separate from the body portion and operatively associated with said smallest size socket annular portions of the body 5 portion to form a larger size socket, said second and third mentioned annular portions of each of all but the smallest size socket comprising a single plate structure including an upwardly embossed portion for leg reception and body centering and a lower outwardly directed peripheral flange portion for engagement with the lower end of the leg.

3. A spring frame type socket for tubular legs including a body portion having an elongated 15 caster stem receiving bore therein terminating in a top bearing for the stem, an annular, grooved portion adjacent the upper end, and an outwardly directed flanged lower end adapted to transmit leg load to the stem, spring frame means 20 swivably mounted in said grooved position, and other means rotatably mounted upon said body and operatively associated with the spring frame means, the said other means including a plate at the lower end of the body.

4. A spring frame type socket for tubular legs including a body portion having an elongated caster stem receiving bore therein terminating in a top bearing for the stem, an annular, grooved portion adjacent the upper end, and an outwardly directed flanged lower end adapted to transmit leg load to the stem, spring frame means swivably mounted in said grooved position, and other means rotatably mounted upon said 30 body and operatively associated with the spring 35 frame means, the said other means including a centering washer at the upper end of the body.

5. A spring frame type socket for tubular legs including a body portion having an elongated 40 caster stem receiving bore therein terminating in a top bearing for the stem, an annular, grooved portion adjacent the upper end, and an outwardly directed flanged lower end adapted to transmit leg load to the stem, spring frame means swivably mounted in said grooved position, 45 and other means rotatably mounted upon said body and operatively associated with the spring frame means, the said other means including a plate at the lower end of the body and a centering washer at the upper end of the body.
